Primary Examiner — Brett Miller*Assistant Examiner* — Jessica M Gebhart(74) Attorney, Agent, or Firm — Fross, Zelnick, Lehrman & Sissu, P.C.; Charles T. J. Weigell, Esq.(57) CLAIM

The ornamental design for a handbag, as shown and described.

DESCRIPTION

FIG. 1 is a front perspective view of a handbag showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The evenly spaced broken lines in the drawings depict stitching that does not form part of the claimed design.
